(57) **CLAIM**

The ornamental design for an accessory holder, as shown and described.

DESCRIPTION

FIG. 1 is a perspective view of an accessory holder as seen from the top, front and left sides wherein the broken line disclosure is for environmental purposes only and does not form a part of the claimed design;

FIG. 2 is a perspective view thereof as seen from the top, rear and right sides thereof;

FIG. 3 is a left side elevational view thereof, the right side elevational view being a mirror image;

FIG. 4 is a front elevational view thereof;

FIG. 5 is a rear elevational view thereof;

FIG. 6 is a top plan view thereof; and,

FIG. 7 is a bottom plan view thereof.
